ALBERT FRIEDMANN, OF WYOMISSING, PENNSYLVANIA.

AUTOMATIC FEEDING AND PUNCHING MECHANISM.

Application filed May 19, 1924. Serial No. 714,378.

My invention relates particularly to automatic feeding and punching mechanism for facilitating quantity production of punched plain and shaped plates for structural and other uses.

My general purpose is to provide for most satisfactorily attaining this obviously important purpose, by means of mechanism of simplified construction and operation. To 10 this end my improved mechanism provides for jointly carrying a sample-punched pattern plate; and a blank plate intended to be similarly punched, by means of a common carrier-table to which successive feed movements are imparted under control of an automatic stop-pin mechanism, and in accord 15 with a like controlled selective punch mechanism adapted to operate upon the blank plate during the feed intervals, as hereinabove fully described in connection with the accompanying drawings illustrating a preferred embodiment of my invention; the novel features of the invention being clearly defined in the subjoined claims.

25 Fig. 1 is a side elevation of a mechanism embodying my invention; the view being in the direction of arrow 1, Fig. 2, and the punch mechanism at the rear being shown partially in cross-section.

30 Fig. 2 is a plan view showing part of the punch machine broken away on the line 2—2 of Fig. 1 so as to show the several punch gags.

Fig. 3 is an enlarged cross-sectional view 35 on the line 3—3 of Fig. 1.

The feed table 15 is adapted to jointly carry a pattern plate B provided with any required number of desiredly spaced apertures, and a blank plate C (dotted lines) in 40 which corresponding apertures are to be automatically punched in succession as the blank plate is moved in determined steps under any number of selectively operative punches 10, 10, 10 carried in the reciprocated 45 ram 11 of the punching machine. As shown the blank plate C is suitably secured to the carrier table 15, which directly carries the pattern plate B, by laterally extending table arms 15^a pivoted to table brackets 15^c; the 50 two plates being laid flat side by side, with the blank plate C in a somewhat higher plane and in advance of the pattern plate as indicated, so that both plates are rigidly carried by the table 15. The plate C only 55 is passed under the punches 10, the pattern plate B passing to one side of the latter un-

der a stop mechanism which properly limits the successive feed movements of the carrier table 15 as hereinafter fully described.

As illustrated, D indicates a punching-machine frame having its bed provided with a changeable die block d, and with a series of anti friction rolls 16, 16 upon which the blank plate C is moved by the laterally extended carrier table 15. The main portion 60 of carrier table 15 is provided with wheels 20, 20 which run on parallel tracks 21, 21 forming part of an annex frame 23 arranged in fixed relation to the punching machine.

The joint step-by-step feeding movement 70 of the pattern and blank plates is effected, as shown, by a friction-connection 25 having adjustably-tensioned slide plates 25^a, 25^b, frictionally engaging the opposite sides of a depending longitudinal rib 15^b of the carrier table 15; to which connection a regular reciprocating movement is imparted in a suitable guideway 23^a (Fig. 3) on the annex frame 23, and the frictional tension of plates 25^a, 25^b, being such as to grip and move the 80 rib 15^b when the carrier table is free to move, or to slide freely on said rib 15^b when the carrier table is held against movement. This regular reciprocating movement of the friction-connection 25 is adapted to impart 85 an irregular feeding movement to the carrier table 15 and its attached pattern plate B and blank plate C, as determined by engagement of one or more stop pins 30, 30, 30 with successive apertures in the pattern 90 plate B; any excess reciprocating movement of the friction-connection 25 resulting in an idle sliding movement of the plates 25^a, 25^b, upon the frictionally engaged table rib 15^b, as above set forth.

The stop-pin mechanism is mounted above the main pattern plate portion of carrier table 15; the stop-pins 30 corresponding with the laterally spaced holes in the pattern B. These stop-pins are vertically guided in the frame portion 23^b (Fig. 3), and are normally depressed by separate springs 30^a, and periodically raised by a cam 35 on shaft 36. This shaft is regularly rotated in synchronism with the reciprocated punch ram 11, 105 and is also provided with a feed cam 37 arranged to operate the friction connection 25 through lever 38 and link 39. The eccentric portion 35^a of cam 35 operates at each rotation upon a vertically guided rod 40, 110 through levers 41, 42, to lift a common pin-raising lever 43; this movement occurring

2
after each punching action of the ram 11 and preliminary to the feed movement of the frictional connection 25. The latter movement carries the table 15 and pattern plate 5 B forward under the raised pins, until springs 30^a depress certain of the latter into a succeeding pattern aperture.

The raising of the stop pins 30 to release the pattern plate B for the next feed movement of table 15, is made to operate upon a gag mechanism for the series of punches 10. This mechanism, as indicated, is essentially such as has been heretofore employed to determine the operativeness of the respective punches, each gag 50 being laterally slidable in the punch block 51 so as to bring an aperture or recess 52 therein into or out of alinement with a vertically slidable punch 10 as indicated, and thereby make the latter 15 ineffective or effective on a succeeding stroke 20 of the ram. I provide that each of the upwardly extending stop pins 30, when raised, shall come into contact with a lever 55, pivoted at 56, so as to cause the opposite end of 25 said lever to swing a gag-contacting lever 57, and thereby inoperatively positioning the corresponding gag 50.

When the cam projection 35^a has passed the forwardly fed pattern plate B will support the pins in raised position until it is stopped by one or more of the pins being automatically lowered into an alined pattern aperture; which lowering releases the corresponding gag and permits its spring 53 to 35 automatically move it so as to make the corresponding punch 10 operative.

The punched plate produced may be an exact duplicate of the pattern plate B, or it may be a structural shape comprising a plate member in which like punchings are made. Both the pattern and blank plates are moved forward by the friction feed device 25 until automatically stopped by stop-pin engagement with the first hole or holes in the pattern plate B, the friction device 25 sliding idly on the table rib 15^b for the balance of its stroke. This plate engaging movement of the stop-pins sets the corresponding punch gags 50 to cause punching of like 45 holes in the blank plate C as the punch ram descends; during which latter movement the friction-feed connection 25 is idly returned to its starting position. The stop pins are then raised by cam 35 to permit another 50 forward friction-feed movement, and to set the punch gags 50 into operative position until they are released by automatic reengagement of certain of the pins with the next hole or holes in the pattern plate for 55 the next punching operation; and so on until the corresponding punching of the blank plate is automatically completed. The stroke of the friction feed device 25 is ordinarily greater than the longitudinal spacing of any 60 succeeding holes, but two or more feed 65

strokes may occur without any effective punching action, the complete reproduction of the pattern punchings being in any case effected automatically.

The particular construction illustrated 70 provides for duplicating in the blank plate at each action of the ram, a maximum of three transversely alined apertures in the pattern plate; the spacing of these being obviously readily varied by correspondingly 75 changing the die block d and punch block 51, and the number of punches and stop pins employed being readily increased if required. As conveniently illustrated the reproduction 80 is reversely punched relative to the placed pattern plate, this merely involving reversal of one or the other plate. The simple means indicated in the drawings for returning the carrier table 15, comprises merely a hand operated pinion-wheel 60 arranged in mesh 85 with a toothed rack 61 on the longitudinal rib 15^b of the carrier table 15, and a hand lever 62 and catch 63 for holding the stop pins in raised position; and there is no showing of drive connections to the punch 90 ram. The feed mechanism comprising the table reciprocating means and the stop mechanism for determining its effective action coincidently with the control of the effective punch action, and other features specifically 95 described may be embodied in modified form without departing from the invention as defined in the claims.

What I claim is:

1. In combination with a punch mechanism, and plate carrier table; a table-feed mechanism comprising a frictionally engaged reciprocative drive connection; and a pattern-engaging stop mechanism comprising stop-pins adapted to automatically determine the effective feed-movement imparted to the table and the selective action of the punch mechanism.

2. An automatic feeding and punching mechanism comprising a common carrier 100 table for pattern-punched and blank plates; a frictionally engaged reciprocative drive connection for said table; a stop-pin mechanism adapted to automatically engage and disengage successively presented holes in 105 said pattern plate; punch mechanism for said blank plate; and means controlled by said pattern plate and stop-pin mechanism for determinedly limiting successive feed movements to the carrier table and simultaneously setting said punch mechanism.

3. In an automatic feeding and punching mechanism comprising a common carrier table for pattern-punched and blank plates, a stop-pin mechanism therefor adapted to automatically engage and disengage successive holes in said pattern plate; punch mechanism for said blank plate operatively controlled in accord with said stop-pin mechanism; and a feed mechanism for said car 115 120 125 130

rier table comprising a regularly reciprocated and normally operative frictionally engaged connection inoperatively slidable thereon when said stop-pin mechanism is pattern-engaged.

4. In an automatic feeding and punching mechanism comprising a common carrier table for pattern-punched and blank plates, a punch mechanism provided with punch 10 gags, means for imparting determined feed movements to said table, means for selectively limiting said feed movements comprising automatically operated stop pins adapted to engage and disengage pattern-apertures in 15 the pattern-punched plate as the latter moves with the carrier, gag positioning means, and mechanical means operatively connecting the gag positioning means and the stop pins, to permit the latter to control the gag 20 positioning means by the aperture engaging and disengaging positioning of said stop pins.

5. In an automatic feeding and punching mechanism, a plate carrier table, a table feeding mechanism comprising a frictionally 25 engaged reciprocative drive connection, a lever attached to said connection, cam actuated means for oscillating said lever, and a pattern engaging stop mechanism comprising stop pins adapted to automatically determine the effective feed movement imparted to the table and the selective action of the 30 punch mechanism.

6. In an automatic feeding and punching mechanism, a carrier table for pattern and 35 blank plates, a stop mechanism including movable elements adapted to engage the pattern plate, a common lever for moving all of said elements in one direction, mechanical

means for actuating said lever, punch selecting gags, and gag positioning means controlled by said elements.

7. In an automatic feeding and punching mechanism, a carrier table adapted to support and move a pattern plate and blank plate arranged edge to edge, means for intermittently feeding the table forwardly, stop pin mechanism adapted to automatically engage successively presented holes in said pattern plate to determinedly limit the feeding movement of said table, punch mechanism for said blank plate selectively positioned by said stop pin mechanism, means for disengaging said stop pin mechanism and simultaneously resetting said punch mechanism preliminary to a successive feed movement of the carrier table, means for returning the carrier table to its initial position, and means for locking the stop pin mechanism in inoperative position.

8. In an automatic feeding and punching mechanism, a common carrier table adapted to support and move a pattern plate and blank plate arranged edge to edge, a transverse frame extending across said table, a rocking lever supported by the frame, punch selecting gags, gag positioning means controlled by said lever, reciprocating stop pins engaging the lever for actuating the latter, a common lever for actuating all of the stop pins in one direction, means for continuously oscillating the last mentioned lever, and continuously operated means for intermittently feeding the table forwardly.

In testimony whereof I affix my signature.

ALBERT FRIEDMANN.
